O. M. LANDIS.

TILE MOUNTING.

APPLICATION FILED APR. 2, 1908.

915,973.

Patented Mar. 23, 1909.

This is an architectural floor plan of a building, likely a residence, featuring a central courtyard and several rooms. The plan is labeled with letters and numbers:

- Rooms:** The plan includes a large room labeled 'a' in the center, a room labeled 'a'' to its right, a room labeled 'a'' to its left, a room labeled 'a'' at the bottom, and a room labeled 'a'' at the bottom left.
- Staircases:** There are two main vertical sections labeled 'c' on the left side, representing stairs.
- Windows:** Several windows are indicated by dashed lines, with labels 'd' and 'd'' pointing to them.
- Doors:** A door is shown on the right side, labeled 'd'.
- Courtyard:** A central courtyard is labeled 'a'.
- Architectural Details:** The plan shows various doorways, windows, and structural details. A curved line labeled 'd' is located on the left side, and a circular opening is labeled 'd' on the right side.

UNITED STATES PATENT OFFICE.

OLIVER M. LANDIS, OF READING, PENNSYLVANIA.

TILE-MOUNTING.

No. 915,978.

Specification of Letters Patent. Patented March 23, 1909.

Application filed April 2, 1908. Serial No. 424,708.

To all whom it may concern:

Be it known that I, OLIVER M. LANDIS, a citizen of the United States, and a resident of the city of Reading, in the county of Berks and State of Pennsylvania, have invented certain new and useful Improvements in Tile-Mounting, of which the following is a specification.

My invention relates to tile mountings in which the tiles are built up in desired patterns adapted to be thereafter applied in required position as a finished design, and it consists in the improved construction hereafter described and specifically pointed out in the claims.

Figure 1 is a front elevation of a tile-mounting embodying my invention in preferred form; a portion of the tiles being removed to show the supporting frame work alone. Fig. 2 is a cross-sectional view on the line 2—2 of Fig. 1.

As shown in the drawings the frame A is adapted for a tile mantel-piece, and it comprises a series of intersecting bars *a a* of tee-shaped cross-section, the flange or head portions *a' a'* of which are all arranged in one and the same plane and serve to support the tiles C; said bars *a a* being made integral, as indicated, with flat marginal bars *d d* arranged to form a shallow tile-receiving box of the required shape, of which box the spaced bars *a a* form the bottom, with their reduced web portions *a² a²* projecting beyond the plane of the marginal bars *d d*. In this frame the tiles are arranged in the desired pattern upon the bottom bars *a a*, in contact with a suitable cement E which fills in the spaces between the bars *a a* and effectually locks the tiles to the latter by closely fitting to the reduced web portions *a² a²* of the bars

under the tile-supporting flange or head portions *a' a'* thereof as indicated.

My invention provides a very simple and satisfactory tile mounting, the construction of which as specifically described and shown 45 may be modified in detail as desired.

What I claim is:—

1. An integrally formed tile-work pattern frame comprising bars of substantially tee-shaped cross-section the flange portions of 50 which are united in a common plane with the web portions projecting on the same side of said plane, in combination with a layer of tiles built-up upon said united flange portions of the bars on the opposite side of said 55 plane and a suitable cement filling in between the projecting web portions of said bars and serving to rigidly secure the tiles to the latter substantially as set forth.

2. An integrally formed tile-work pattern 60 frame having flat marginal bars forming a shallow tile-receiving box, and intersecting bottom-bars of substantially tee-shaped cross-section the flange portions of which unite with said marginal bars and the web portions of which all project on the same side beyond the plane of the latter, in combination with tiles arranged in said frame on the side opposite to said web portions and a suitable cement filling in between the projecting 65 web portions of said bottom bars and serving to rigidly secure the tiles to the latter substantially as set forth.

In testimony whereof, I affix my signature, in the presence of two witnesses.

OLIVER M. LANDIS.
